(57) **CLAIM**

The ornamental design for a tool holder for an electronic device, as shown and described.

DESCRIPTION

FIG. 1 is a perspective view including the front, side, and end of a tool holder for an electronic device;

FIG. 2 is a perspective view including the rear, side, and end of the tool holder for an electronic device;

FIG. 3 is a front elevation view of the tool holder for an electronic device;

FIG. 4 is a rear elevation view of the tool holder for an electronic device;

FIG. 5 is a side elevation of the tool holder for an electronic device;

FIG. 6 is an opposite side elevation view of the tool holder for an electronic device;

FIG. 7 is an end elevation view of the tool holder for an electronic device; and,

FIG. 8 is an opposite end elevation view of the tool holder for an electronic device.

1 Claim, 6 Drawing Sheets
